UNITED STATES PATENT OFFICE

2,536,447

COMBINATION SQUARE AND LEVEL

Thomas A. Kirton, Jacksonville, Fla.

Application October 2, 1946, Serial No. 700,694

2 Claims. (Cl. 33—89)

1

This invention relates generally to the class of geometrical instruments and pertains particularly to improvements in direction indicators.

In the construction of buildings an initial operation is the determination of levels for the construction of a level foundation. This is ordinarily done by the placing of stakes or boards at corners of the foundation and leveling a line running between such boards by means of a spirit level. In other cases use is made of a transit. In both of these methods of leveling the foundation line, inaccuracies occur.

The object of the present invention is to provide an improved device for setting level lines between the batten boards which are set into the ground at the different corners of a foundation, whereby an absolutely accurate leveling of the foundation line is possible with a minimum of effort.

Another object of the invention is to provide an improved leveling device comprising a combination of a steel square, cord and plumb bob.

The invention will be best understood from a consideration of the following detailed description taken in connection with the accompanying drawing forming a part of the specification, with the understanding, however, that the invention is not confined to a strict conformity with the showing of the drawing but may be changed or modified so long as such changes or modifications mark no material departure from the salient features of the invention as expressed in the appended claims.

In the drawing:

Figure 1 is a view in elevation showing the present invention, in applied position upon two batten boards.

Figure 2 is a view in top plan of the structure shown in Figure 1.

Figure 3 shows the manner of using the invention close to the ground surface.

Referring now more particularly to the drawing, Fig. 1 illustrates the device of the present invention and a method of using the same for marking or indicating a level elevation plane on two batten boards set up at two corners of a foundation line.

In this figure the numeral 10 generally designates the ground line and the numerals 11 and 12 designate two batten boards which may represent two corner positions of a building foundation line or location.

In accordance with the present invention, there is provided a steel square 13 of a type commonly employed by carpenters. Such a square has a

2

long arm 14 and a short arm 15 extending at right angles thereto from one end thereof.

At the joined ends of the two arms of the square there are provided the two apertures 16 which are spaced apart along a line extending longitudinally of the long arm 14 and adjacent to the outer longitudinal edge thereof. At the outer or free end of the long arm 14 in line with the two apertures 16 a gauge line or mark 17 is made on the square arm or blade.

At the outer end of the short arm or blade 15 a gauge line or mark 18 is located which is spaced from the adjacent outer longitudinal edge of the arm 15 at the same distance as the opening 16 15 which is nearest to this edge. Thus a line drawn from the gauge line 17 through the two openings 16 will be perpendicular to a line drawn from the gauge line 18 to that one of the openings which is nearest to the outer longitudinal edge of the arm 20 or blade 15.

In addition to the openings 16, the arm or blade 15 of the square has an opening 19 formed therethrough at the inner end of the gauge line 18 to be used in the operation of setting a level line 25 near the ground surface.

In association with the steel square 13 there is used the line 20 upon one end of which is secured the plumb bob 21. This line is threaded through the two openings 16 in the manner illustrated so that a portion of the line lies along the face of the short blade 15 and another portion may be stretched out to extend along the face of the long blade or arm 14 of the square.

The free end of the cord 20 is attached to a nail or other securing element 22 which is fastened in one batten board, for example, the board 12, and the square is then placed against the other batten board in the manner illustrated, that is, with one blade or arm extending horizontally and the other one extending vertically and downwardly. A knot 23 is made in the line between the openings 16 and the user of the device then pulls the square away from the fixed point 22 so as to draw the horizontal portion of the line taut. By then raising or lowering the square the horizontal and vertical portions of the line may be brought into position to lie over the adjacent gauge lines 17 and 18 so that the vertical part of the line to which the plumb bob 50 is attached will be perfectly vertical and directly in front of the gauge line 18. When this condition is obtained then the portion of the line running from the batten board 11 to the board 12 will be perfectly horizontal and a mark may be placed on the batten board 11 as indicated

at 24 to designate the same level as the point 22 on the other board.

Where it may be necessary to strike a level line near the surface of the ground the device may be used in reverse, it being understood, of course, that both faces of the square blades or arms will be provided with the gauge lines 17 and 18. This reversed position for the use of the device is shown in Figure 3, wherein the long arm or blade of the square is disposed in close proximity to the ground and the short arm is disposed vertically. When used in this position two separate lines 25 and 26 may be used although, as will be readily apparent, it would be possible to use a single line as in the first described manner of using the instrument.

In this second use of the instrument, the line 25, assuming that two separate lines are used, has an end extended through the opening 19 and a knot may be formed on the end to keep the same from escaping from the opening. The plumb bob 27 is then positioned with its point in close proximity to the outer one of the two openings 16, by which is meant that opening nearest to the outer longitudinal edge of the short arm or blade 15. The square is then adjusted until the point of the plumb is directly over the center of the outer opening 16 whereupon the lower arm or blade 14 of the square will be horizontal. The line 26, attached at one end to the inner one of the openings 16 and at its other end to a post, pin or other suitable attaching means, not shown, will then be brought into position across the gauge line 17 and will be perfectly horizontal. A post or stake 28 may then be driven down to the level of the line 26 to fix such level.

From the foregoing it will be readily apparent that there is provided in the present invention a simple and inexpensive instrument by means of which relatively long foundation and other lines may be quickly leveled with extreme accuracy.

While in the description of the use of the instrument as shown in Figure 1 it has been stated that the cord 20 is in a single piece extended through the two openings 16, it will be readily apparent that although this is the preferred

manner of using the device, such cord may be in two sections, one of which might be secured in one opening 16 and attached to the fixed point 22 and the other secured at one end in the other opening 16 and having the plumb bob attached to its other end. Accordingly, in referring in the claims to a pair of cords it is to be understood that each of the two sections may be considered as separate cords as well as parts of a single cord.

I claim:

1. A leveling instrument comprising a square having two right angularly related blades, a gauge line upon a side face of each blade adjacent to the free end thereof, one of the blades having a pair of apertures formed therethrough at its inner end, the apertures being spaced apart on a line extending lengthwise of the said one of the blades, the line upon which the apertures are located being parallel with the outer edge of the said one of the blades and passing through the gauge line at the outer end of the said one of the blades and perpendicular to a line drawn from one of the apertures through the other gauge line, cord sections each engaging at one end in an aperture, and a plumb bob attached to the other end of one of the cord sections.

2. A leveling instrument of the character stated in claim 1 wherein the other one of the blades has an aperture therethrough adjacent to its free end and in a line passing from the adjacent gauge line to one of the first mentioned apertures.

THOMAS A. KIRTON.
